MOULDS FOR CASTING SINGLE-TYPE BODIES

Robert Alfred Jupp, Horley, and Maurice Richard Dewhurst, Coulson, England, assignors to The Monotype Corporation Limited, London, England, a British corporation

Application December 6, 1954, Serial No. 473,248

2 Claims. (Cl. 199—87)

This invention relates to moulds for casting single-type bodies and particularly to such moulds as are used in type-casting and composing machines, the operations of which are governed by a prepared controlling or record strip and wherein type-matrices are assembled in rows and columns in a frame or carrier movable relatively to the type mould, to position the selected matrix over the mould cavity.

More particularly, the invention relates to moulds for the production of type-bodies with characters in Arabic or other oriental languages, wherein the characters may extend to a greater extent beyond the centre line of the body than they do with Roman or Latin characters, or where an accent may be added at the top or at the foot of the character.

One of the chief difficulties in dealing with oriental languages is in providing sufficient matrices for a satisfactory font in a single matrix carrier, the theoretical dimensions of which may not be limited, but which for practical purposes must be limited.

Such moulds, as hitherto constructed and with relation to which an embodiment of the invention will now be described, have been furnished with a main dimensioning blade extending to the full point size of the mould and a cut-off blade having a forwardly extending portion fitted into a shoulder or cut away part on one upper corner in the main blade, is of less than full point size. These blades, when operated together, dimension the mould for a type body and a character bearing end, both of full point size, but when only the main blade is withdrawn to open the mould cavity and the cut-off blade is projected to close a corresponding part of the upper end of the mould cavity, the resulting type body is cast of full point size; but the character bearing portion is of less than full point size.

The operations of both main and cut-off blades in the known mould are controlled by a perforated controlling-ribbon, the actuation of the main blade being designated or determined and also operated by mechanical devices while the actuation of the cut-off blade is designated or determined by an air-operated motor and operated by mechanical devices.

According to the present invention, the movements of the cut-off blade are both designated or determined by pneumatic devices and the actuation of this blade is also effected by pneumatic devices in proper timed relation to other movements of the machine during a cycle of operation.

The invention will now be described with reference to the accompanying drawings wherein

Fig. 1 is a front elevation of part of an existing type-casting and composing machine in which the mechanism of the present invention is incorporated.

Fig. 2 is a plan view of the mechanism shown in Fig. 1.

Fig. 3 is an elevation of the same mechanism as viewed at a right angle to Fig. 1.

Fig. 4 is a sectional elevation of part of the pneumati-

2

cally operated device for controlling the movement of the cut-off blade according to the present invention.

Fig. 5 is a sectional elevation as viewed at an end, partly in section right angles to Fig. 4 and on the reverse side of Fig. 3.

Fig. 6 is a perspective view of the mould, with main and cut-off blades moved back to dimension the mould cavity.

Fig. 7 is a similar view showing the mould in which the cut-off blade forming part of the present invention is in the forward or cut-off position.

Fig. 8 is a similar view showing the main blade and the cut-off blade of the present invention moved back to dimension the mould.

Figs. 9, 10 and 11 are perspective views of the upper portions of type bodies as produced with setting of the blades respectively according to Figs. 6, 7 and 8.

Fig. 12 is a diagrammatic view, showing the air circuits, air valves and air motor according to the present invention.

The type mould in its general features is of well known construction and comprises a frame A, two side blocks A¹ (only one of which is shown in Fig. 6), which form two side walls of the casting cavity *a* and between which 25 the main mould-dimensioning blade B is a close sliding fit. In the base A³ of the mould, underneath the main blade B, is an inlet A⁴ for molten metal (see Fig. 6). The existing cut-off blade B¹ rests upon a cut away portion on the upper side of the main blade B and is furnished with an extension B² at its forward end, which normally has its forward end flush with the forward face of the blade B and its upper surface is level with the upper face of the blade B.

The cut-off blade B³ according to the present invention fits into a longitudinal recess in the upper surface of the main blade B (see Figs. 6-8) and in the rearward position, the rear end of this blade bears against a shoulder *b* on the main blade B. At its forward end, this cut-off blade B³ has an upwardly extending portion B⁴ and a forwardly extending projection B⁵ which is a sliding fit on a shoulder on the forward end of the blade B. On its under side, the blade B³ is furnished with a slot B⁶, into which fits one end of a lever C¹ which is actuated by a bar C², coupled to a pneumatic motor C (see Figs. 1, 6 45 and 12).

The supply of air to this motor C is controlled indirectly by perforations in the controlling strip which controls the supply of air for various operations of the type casting machine.

In the embodiment of the invention now to be described, two ports X, X¹ in the existing air supply bar X² (Fig. 12) are employed, but these two ports do not together form an operating air signal in the normal running of the machine. When perforations in the perforated control strip are presented at the air bar X² to uncover ports X, X¹, when the air from port X enters an inlet D¹ in a duplex air-valve box D, which diverts required air from its normal function to control mechanism of the present invention. This diverted air enters 55 the box D beneath a piston D² therein which it raises. Simultaneously, air from port X¹ enters the valve box D through an opening D³ and the piston D² being raised, this air passes now round the piston and out by an opening D⁴ and is conducted by a pipe D⁵ to one of an air 60 chamber D⁶ in which there is a slide or piston D⁷. This slide D⁷ is retained at one end of the chamber D⁶ by a spring D⁸ and the air pipe D⁵ enters this chamber at the end opposite to the spring D⁸ (see Fig. 12).

Attached to this air chamber D⁶ is a valve box D⁹ 65 wherein are arranged two spring loaded air control valves D¹⁰, D¹¹, and a pipe D¹² leading to the chamber in which these valves are situated is coupled to a constant air

supply. The valve D^{10} controls the flow of this air, through a pipe D^{13} to one end of the cylinder of the motor C and the valve D^{11} similarly controls the flow of air through a pipe D^{14} to the other end of motor C (see Fig. 12).

A diamond shaped directing member D^{15} (see Figs. 3, 4 and 5) pivotally supported on a stationary support at d (see Fig. 4), is furnished with a pin d^1 which projects into a groove d^2 in the piston D^7 (see Fig. 12) through a slot d^3 in the slot of the air chamber D^6 and will be set by the movements of this piston as dictated by either the valve D^{10} or the valve D^{11} , and determine by positioning the lever E whether the cut-off blade B^3 will be drawn back to open the part of the mould controlled by it and in conformity with the positioning of the main blade B, or will be placed in its forward position to shorten a part of the mould cavity and relatively to the main blade B which will be moved back to dimension the mould in the width direction of a type body.

An operating lever E (see Figs. 1-6) is pivoted to an existing arm F on the casting machine, which is raised and lowered once in each cycle of operations of the machine. The lever E is maintained against accidental displacement by a spring E¹.

Owing to peculiarities in the cycle of operations of the type-casting machine to which the invention applies, the combined signal X X¹ is applied to the air supply bar X² somewhat in advance of the point at which the mould can be dimensioned by the mould blades. When this combined signal X X¹, which controls the pneumatic devices of the invention, is presented at the air supply bar X², the rocking arm F is in its lowest position for the casting of a previously designated type body for which the mould blades have already been positioned.

The normal position of the directing piece D^{15} is shown in Fig. 5, in which position it is maintained, or to which it is returned by the spring D⁸ acting on the slide D⁷.

When the arm F is moved upwards carrying with the lever E, this lever E will engage the directing piece D^{15} and be positioned to operate on the next downward stroke of the arm F either the valve D^{10} or D^{11} .

In the absence of the combined signal X X¹, the lever E will, in the down stroke of the arm F, act on the valve D^{11} and the air will move piston of the motor C to position shown in Fig. 12 and maintain the cut off blade in the position shown in Fig. 7.

When the combined signal X X¹ is presented, the cut-off blade will be moved to the position shown in Fig. 6, the directing member D^{15} will be set in the position shown in Fig. 5 by the air during the upstroke of arm F so that in the succeeding down stroke of arm F the lever E will act on the valve D^{10} and admit air to the cylinder of piston C to act on lever C¹ and move the blade B^3 to the position shown in Fig. 6.

Before the arm F is raised however, air will have entered the cylinder of the slide D^7 and during the upward stroke, the directing piece D^{15} will be set to position the lever E and open one or other of the valves D^{10} , D^{11} , so that on the next down stroke of the arm F, depending upon the setting of the directing piece D^{15} and the motor C, will transmit the correct setting to the mould blade B^3 .

The air ports X, X¹, used for the purposes of the invention, are separately used as components of air signals for positioning a matrix carrier and other purposes. Where so used, the air through the port X passes to a position Y of the matrix-positioning mechanism and part of this air may enter the valve box D without any effectual action. Similarly, air through the port X¹ will enter the valve box D and pass around the piston D² and thence to the position Y¹ of the matrix positioning mechanisms.

The cut-off blade B¹ may be moved independently of the blade B³ from the position shown in Figures 6 and 7 to the position shown in Figure 8, to shorten a part of the mould cavity on the side opposite to that on which shortening is effected by the blade B³, so that such shortening may be produced on either side, or on both sides of the cavity. The mechanism for determining the movements of the blade B¹, and for actuating it are of known type and do not form part of the present invention.

20 What we claim is:

1. In a single-type casting mould furnished with a main full-point size dimensioning blade and a cut-off dimensioning blade, the arrangement of an air operated motor for actuating the cut-off blade, two valves coupled to a constant supply of air and separately controlling the supply of air to the air operated motor for the cut-off blade, a piston operated intermittently by air controlled by signals in a perforated record strip a directing piece, means coupling the directing piece to the air operated piston whereby the directing piece is set by the movement of said piston, an intermittently operated rocking arm, means on said rocking arm defining a pivot moving in a fixed path with said rocking arm, and a lever mounted on said pivot for movement with said rocking arm, said lever being directed by said directing piece to follow either one of two paths during movement of the rocking arm and so to operate one or the other of the two valves coupled to the air motor for the cut-off blade.

2. In a single-type casting mould furnished with main and supplementary mould-dimensioning blades, the combination with an air operated motor coupled to the supplementary blade, a spring-loaded and air operated piston coupled with a directing piece, separate valves for the air motor coupled to the supplementary blade and communicating with a constant air supply, an operating lever carried on a rocking arm for separately operating the valves for the motor for the supplementary blade and an air valve controlled by separate signals in a record strip to admit air to the piston and set the directing piece, between the downward and upward movement of the rocking arm.
